(57) **CLAIM**

The ornamental design for a triangular lamp, as shown and described.

DESCRIPTION

FIG. 1 is a top, front, and left side perspective view of a triangular lamp showing our new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a left side elevational view thereof;

FIG. 7 is a right side elevational view thereof;

FIG. 8 is a bottom, front, and left side perspective view thereof; and,

FIG. 9 is an enlarged view of a portion of the triangular lamp shown within the area designated as 9 in FIG. 8.

The broken lines in the drawings illustrate portions of the triangular lamp and form no part of the claimed design.
